UNITED STATES PATENT OFFICE.

ADAM J. YAEGER, OF RHODES, IOWA.

BINDER.

1,197,884.

Specification of Letters Patent.

Patented Sept. 12, 1916.

Application filed November 11, 1915. Serial No. 60,961.

To all whom it may concern:

Be it known that I, ADAM J. YAEGER, a citizen of the United States, and resident of Rhodes, in the county of Marshall and State 5 of Iowa, have invented a certain new and useful Binder, of which the following is a specification.

The object of my invention is to provide a binder of simple, durable and inexpensive 10 construction.

A further object is to provide such a binder having parts so constructed and arranged that the grain can be handled without the necessity for elevating it to any substantial height as for the purpose of clearing 15 the reel or the like.

Still a further object is to provide such a binder so constructed and arranged that the parts may be properly supported on wheels 20 and so located as to make it unnecessary to raise any part of the grain handling mechanism except the reel.

Still a further object is to provide such a grain binder having its wheels at the end 25 of the machine where the larger part of the grain handling is done, and so located and arranged that the power shaft may be located in front of the machine and adjacent to the part thereof where most of the grain 30 handling is done, in which machine the grain handling mechanism may be operated from such power shaft.

Still a further object is to provide such a machine so constructed and arranged that 35 the grain handling mechanism may be operated from the traction wheel or wheels located in front and near one end of the body of the machine.

My invention consists in the construction, 40 arrangement and combination of the various parts of the device whereby the objects contemplated are attained, as hereinafter more fully set forth pointed out in my claims, and illustrated in the accompanying drawings, 45 in which:

Figure 1 shows a top or plan view of a grain binder embodying my invention. Fig. 2 shows a rear elevation of the same. Fig. 3 shows a sectional view taken on the line 3—3 50 of Fig. 1; Fig. 4 shows a side elevation of the front truck. Fig. 5 shows a vertical sectional view taken on the line 5—5 of Fig. 1. Fig. 6 shows a vertical, central sectional view through the gearing device on the front 55 truck, taken on the line 6—6 of Fig. 7. Fig.

7 shows a horizontal sectional view taken on the line 7—7 of Fig. 6.

In the accompanying drawings I have used the reference numeral 10 to indicate generally the frame of my improved binder, 60 which has the ordinary grain platform 11, upon which the grain drops after having been cut by the sickle and aided by the ordinary reel 12.

At one end of the platform 11 is a supporting wheel 13. At the other end of said platform is a binder platform 14 part of which is formed by an endless carrier. The binder platform is arranged substantially at the same height as the grain receiving platform 11 over which travels the endless carrier 16.

Suitably supported on the frame rearwardly of the binder platform is a caster wheel 17. Spaced forwardly from the 75 binder platform is a truck comprising a shaft or axle 17, on the end of which are supporting wheels 18. On the shaft or axle 17 is a sleeve 19 having the portion 20 spaced from the portion 19 and connected 80 therewith by a U-shaped member 21.

Fixed on the axle 17 between the sleeve portions 19 and 20 is a beveled gear 22. On the sleeve 19 preferably formed integral therewith is an upwardly extending cylindrical member 23, the walls of which are connected above the body of the sleeve 19 with a webbing or partition 24. The partition or webbing 24 is located above the upper edge of the cylindrical member 23, as 90 shown in Fig. 6. Spaced outwardly from the member 23 is an annular extending flange or ring 25. On the rings 25 are mounted several short shafts 26, on which are mounted rollers 27 outside the ring 25. 95

Resting upon the web or partition 24 and also upon the upper end of the portion 23 is the lower central portion of a socket member 28, forming half of a socket. At the upper edge of the member 28 is a laterally 100 extending flange 29 on the outer edge of which is a downwardly extending flange 30, which rests upon the rollers 27. A gear 31 is formed on the lower end of the flange 30, as shown in Fig. 6, and is in mesh with the 105 gear 22. Above the socket 28 is a socket member 32, forming the upper half of the socket.

Received in the socket, heretofore described, is a ball 33 having a slot 34. The 110

socket members 28 and 32 are provided on opposite sides with adjacent inwardly extending lugs or fingers 36.

The cutting and binding mechanism may 5 be of the ordinary type, and form in their details no part of my present invention. The only change from ordinary types of such mechanism is that involved in doing away with the large tractor wheels, commonly employed, and the necessity for elevating the grain over said wheel.

Formed on the ball 33 is an upwardly extending shaft or stem 37, which extends through an opening 38 in the top of the 15 socket member 32, which opening is of greater size than the shaft 37. Mounted on the shaft 37 above the socket member 32 is a sleeve 39 having at its lower end a concave cover member 40 adapted to cover the 20 opening 38 and to receive the upper portion of the socket member 32 and to slide thereon. At the upper end of the sleeve 39 is an annularly extending flange 41 adapted to serve as a supporting base, for a tongue member 25 42. The tongue member 42 extends rearwardly, and is rigidly connected with the frame 10 of the binder.

Resting above the forward end of the tongue member 42 is a bearing 43 for the 30 shaft 37. Formed on the bearing 43, at one end thereof, is an upward extension 44, forming a bearing for a rearwardly extending shaft 48. On the shafts 37 and 48 are beveled gears 49 and 50 which mesh with 35 each other. The shaft 48 extends rearwardly above the binder platform near the rear part thereof, operatively connected by suitable gearing devices 51, 52, 53 and 54, and the like with the various operating mechanism 40 of the binder including the binder shaft and discharging mechanism, the sickle bar and the reel.

In building a binder of the type herein 45 constructed, one of the problems faced is that of permitting the truck to swing laterally for making turns and for giving flexibility to the device, and also permitting the axle 17 to tilt in a vertical plane when the wheels 18 strike inequalities in the ground.

50 It is desirable, therefore, where the mechanism of the binder is run from the wheels, that a mechanical connection should be made between the axle 17 and the operative mechanism of the binder which will permit such movement of the axle. I have, therefore, devised the ball and socket construction, hereinbefore described, whereby the gear 31 is rotated from the axle by means of the gear 22. The lugs or fingers 55 36 received in the slot 34 rotate the ball 33 and the shaft 37 from which the operative mechanism of the binder is run. It will be seen that the axle may tilt in a vertical plane and that the members 36 60 65 may travel upwardly or downwardly in the

slot 34, or that the ball may swing as on a pivot, so as to allow free movement of the truck wheels. In this connection it may be noted that the greatest diameter of two adjacent members 36 is slightly less than the 70 width of the slot 34, so as to permit such pivotal movement.

In a binder of this type, the ordinary large tractor is dispensed with, whereby it is made unnecessary to elevate the grain, 75 and it follows that it is thus possible to save the power ordinarily employed for such elevations. A convenient and facile means for operating the mechanism of the binder from the truck wheels has been shown. Any other 80 suitable means for operating such mechanism may be employed. The parts are so constructed that an engine could be located on the frame in front of a binder platform, if desired.

85 It will be understood that numerous changes may be made in the construction and arrangement of the parts of my improved binder, without departing from its essential features and purposes, and it is 90 my intention to cover by this application any such changes which may be included within the scope of my claims.

I claim as my invention:

1. In a device of the class described, a 95 frame for supporting harvester mechanism, a supporting wheel at one end thereof, a supporting wheel rearwardly of the frame near the other end thereof, a truck forwardly of the frame at the latter end thereof, said truck having an axle wheel thereon, a sleeve on said axle, a rotatable member supported on said sleeve having gear teeth and having a socket formed in its upper portion with opposite inwardly extending lugs, a gear 100 on said axle in mesh with said gear teeth, a socket member mounted above said first described socket member having opposite inwardly extending lugs above the first described lugs, said second socket member having an opening in its upper portion, a ball 105 received in said socket members having a shaft thereon extending upwardly through said opening, said shaft being of smaller diameter than the opening, said ball having 110 in its surface a slot for receiving said lugs, a sleeve on said shaft above said upper socket member having at its lower end a concave cover member for said upper socket member, a tongue on said frame resting upon said sleeve, said shaft being extended through said tongue, a second shaft, a bearing therefor on said frame, bearings on said tongue for both of said shafts and co-acting gearing devices on said shafts, 115 said second shaft being extended to said frame for operating mechanism thereon.

120 2. In a device of the class described, a frame for harvesting mechanism, supporting wheels near the opposite ends thereof, 125

a tongue extending forwardly from said frame, a truck forwardly of the frame near one end thereof having a traction wheel, a supporting member above said truck, a shaft rotatably mounted therein, said tongue member being supported by said supporting member at its forward end and having said shaft extending through it, means for operatively connecting said traction wheel with said shaft so arranged that the shaft may remain in upright position while permitting considerable variation in the position of the truck due to irregularities in the contour of the ground over which the machine travels, a shaft operatively connected with said first shaft and extending toward said frame for operating mechanism thereon.

3. In a device of the class described, a frame for harvesting mechanism, supporting wheels therefor near the ends thereof, a truck forwardly of said frame near one end

thereof having an axle, a wheel on said axle, a supporting member above said axle, an upright shaft rotatably mounted in said supported member, a tongue extending forwardly from said frame having its forward end resting upon said supporting member and receiving said shaft and means for operatively connecting said shaft and said axle for imparting rotary motion to the shaft from the axle when the shaft is upright, while permitting considerable variation in the position of the wheels of said truck due to inequalities in the surface of the ground, a shaft operatively connected with said first shaft and extending toward said frame for operating mechanism thereon.

Des Moines, Iowa, October 6, 1915.
